VALVE MECHANISM FOR STEAM PLANTS

Richard Köller, Bremen, Germany; vested in the
Alien Property CustodianApplication September 7, 1939, Serial No. 293,695
In Germany December 5, 1938

2 Claims. (Cl. 137—153)

One object of the present invention is to provide new and improved means for operating and controlling the main stop valve and fuel oil valve of a power plant steam boiler, in such a way as to afford increased safety in the operation of said plant. The invention is particularly adapted for use in ship power plants, operating under high pressure and temperature, although as far as certain aspects of the invention are concerned, it may be used in conjunction with any steam generating plant.

As a feature of the present invention, there is provided hand controlled means for operating both the fuel oil valve and the main stop valve of a boiler plant simultaneously into open or closed position.

As a further feature, means are provided for operating the main stop valve independently of the position of the hand controlled means.

As another feature, the fuel oil valve may be operated into open position independently of the position of the hand controlled means.

As another feature, there is provided a safety device, operated by steam pressure for closing the main stop valve and the fuel valve automatically and independently of the position of the hand controlled means, when the pressure in the steam mains drops below a predetermined amount with respect to the boiler pressure. This construction affords additional safety means for closing the main stop valve when defects such as fractures or large leaks appear in the steam mains.

Various other objects, features and advantages of the invention will be apparent from the following particular description, and from an inspection of the accompanying drawings, in which:

Fig. 1 is a longitudinal section through one form of construction embodying the present invention, parts thereof being shown somewhat diagrammatic,

Fig. 2 is a section taken on line 2—2 of Fig. 1,

Fig. 3 is a longitudinal section of another form of construction embodying the present invention, parts thereof being shown somewhat diagrammatic,

Fig. 4 is a transverse section taken on line 4—4 of Fig. 3, and

Fig. 5 is a section taken on the line 5—5 of Fig. 3.

In the specific form of the invention shown in Figs. 1 and 2, there is provided a fuel oil valve 10 for controlling the fuel to a boiler (not shown), a main stop valve 11 connected to the

outlet of said boiler, and a hand controlled device 12 for operating said valves simultaneously.

The fuel oil valve 10, which may be of the slide type, is shown comprising a valve casing 15, and a valve member 16 therein, co-operating with a valve seat 17 between the inlet and outlet sides of said valve, and secured to one end of a stem 18. This stem 18 is guided for axially slidable movement in a fixed guide plate 20, and is urged upwardly in the valve closure position shown in Fig. 1 by means of a coil spring 21, encircling said stem and seated at one end on said guide plate, and abutting at its other end a collar 22 affixed to said stem.

The main stop valve 11 comprises a valve casing 25, having an inlet 26, connected to the outlet side of the boiler drum or boiler steam collector by means of a flange 27, and an outlet 28 connected to the steam mains, feeding the various prime movers of the power plant such as the steam engines. Between this inlet and outlet is a valve member 30, adapted to co-operate with a valve seat 31.

The motive means for operating the stop valve 11 comprises a control piston 32, reciprocable in a cylinder 33, and rigid with the valve member 30 through an interconnecting piston rod 34. The cylinder 33 is provided at opposite ends with ports 35 and 36, having steam pressure connections by which the piston 32 can be moved in closure or open position of the valve 11, according to the position of the hand controlled device 12, as will be hereinafter described.

The hand controlled device 12 includes a change-over valve 39, which controls the operation of the piston 32, and which comprises a valve casing 40, and a double cone valve member 41 therein, with its two conical faces adapted to co-operate respectively with seats 42 and 43.

This valve member 41 is secured to a stem 44, having an intermediate portion 45 threaded in the valve casing 40, and one end connected to a crank shaft 46. This crank shaft 46 is journaled in a frame bracket 47, secured to the valve

casing 40, and has affixed to one end thereof a suitable operating handle 48. The connection between the crank shaft 46 and the valve stem 44 is such as to effect rotation of these members together, while permitting said stem to move axially with respect to said crank shaft. For that purpose, the stem 44 has its outer end 50 substantially of rectangular cross-section, slidably fitted into a correspondingly shaped socket at the end of the crank shaft 46. As the handle 48 is rotated, the corresponding rotation of the

valve stem 44 causes said stem to move axially as the result of its threaded engagement with the valve casing 40, so that the valve member 41 is moved into seating engagement with either one of the seats 42 or 43.

On one side of the seat 42 is a valve chamber 55, which is under boiler pressure at all times by means of a pipe 56, forming one of the branch connections of a pipe 57 communicating with the inlet side 28 of the main stop valve 11, the other branch connection 58 being connected to the port 35 to deliver steam under boiler pressure to the upper side of the piston 32. A valve 60 in the line 57 is continuously kept in open position by a suitable plug, so that the full boiler pressure is effective through the branch connections 56 and 58.

On the other side of the seat 42 is a pair of ports 61 and 62 on opposite sides of the valve seat 43, and in communication with each other through an intermediate valve chamber, when the valve member 41 is in seating engagement with the seat 42 as shown in Fig. 1. Connected to the port 61 is one end of a pipe 63, the other end being connected to the port 36. The other port 62 has a pipe connection 65 leading to the exhaust side of the power plant units, such as the steam engines.

When the valve member 41 of change-over valve 39 is in the position shown in Fig. 1 in engagement with the valve seat 42, the valve chamber 55 is shut off from communication with the ports 61 and 62, while said ports are in communication with each other, so that the pipe 63 is under low exhaust steam pressure. Under these conditions, the underside of the piston 32 will be under the exhaust pressure in the pipe 63, and since the upper side of the piston 32 is under boiler pressure at all times, the resultant downward steam pressure on said piston will cause said piston to move downwardly, until the valve member 30 engaging the seat 31 closes off flow of boiler steam to the outlet 28 and into the steam mains.

When the handle 48 is turned in a direction to move the valve member 41 to the left from the position shown in Fig. 1 into engagement with the seat 43, communication between the two ports 61 and 62 will be cut off, and the valve chamber 55 will be in communication with the port 61. Under these conditions, the pressure on opposite sides of the piston 32 being equalized, the boiler steam pressure acting on the under side of the valve member 30 will move said member upwardly into open position to permit flow of steam through the stop valve 11 into the steam mains.

The stop valve 11 may be closed independently of the change-over valve 39. For that purpose, there extends from the piston 32, and through one end of the cylinder 33, a rod 66, reduced in diameter at one end to form an annular shoulder 67. Loosely encircling this reduced section of the rod 66 above the shoulder 67 is a sleeve 68, which has a splined connection with a bevel gear 69, meshing with bevel pinions 70, and which is threaded to a frame structure 71. Upon rotation of the pinions 70, the resulting rotation of the sleeve 68 will move said sleeve axially along the reduced end of the rod 66. This sleeve 68 can be moved downwardly sufficiently to close the valve 11 by the seating engagement of said sleeve 68 with the shoulder 67 of the rod 66, independently of the change-over valve 39, or can be raised with respect to the rod 66 in posi-

tion to limit the extent of opening of the stop valve 11.

In order to operate the fuel oil valve 10 simultaneously with the main stop valve 11, the crank 5 shaft 46 has a cam 73, desirably integral therewith, and cooperating with a lever 74, one end of which is pivotally secured at 75 to the frame bracket 47. This lever 74 carries intermediate its ends a roller 76, pressed into follower engagement with the cam 73 by the action of coil spring 21 acting on valve stem 18. In the position shown in Figs. 1 and 2, the high part 77 of the cam 73 being out of engagement with the follower roller 76, the lever 74 will be in its extreme counter-clockwise position shown, so that the valve member 16 will be pressed into closure position against the valve seat 17. When the handle 48 is rotated in position to open the stop valve 11 as already described, the high portion of the cam 73 moving into engagement with the follower roller 76, rotates the lever 74 clockwise about its pivotal support, so that the valve stem 18 is pressed downwardly against the action of the coil spring 21 to open the valve 10.

The handle 48 is desirably provided with a device 78 for indicating open and closed position of the two valves 10 and 11. When the handle 48 is turned into indicated closed position shown in Figs. 1 and 2, both of these valves 10 and 11 will be closed, and when turned into indicated open position, both of these valves will be open.

Means are provided for holding the fuel valve 10 open, independently of the operation of the hand device 12. For that purpose, the free end of the lever 74 can be locked to an ear extension 79 of the frame bracket 47 by means of a locking pin 80, when said lever is rotated clockwise in position in which the fuel valve 10 is open.

In the form of the invention shown in Figs. 3 and 4, the hand device 12a for simultaneously operating the fuel oil valve 10a and the main stop valve 11, comprises an elongated casing 81, an operating handle 48a, a valve 39a for controlling the operation of the main stop valve 11 upon operation of said handle 48a, and connecting means between said handle and said valve 39a. This valve 39a comprises a valve casing 82, and a double cone valve member 83, connected to a stem 84, and adapted to co-operate respectively with seat members 85 and 86 on opposite sides thereof. Between the two valve seats 85 and 86 is a port 61a, to which is connected pipe 63. The valve seat 85 is disposed between port 61a and a port 62a, having a pipe connection 65 to the steam exhaust side of the prime movers, such as the steam engines. Connected to the underside of the valve member 83 is a rod 87, having a non-conforming slide fit in the valve seat member 86 as shown in Fig. 4, to permit flow of fluid through said seat member in the position of said valve member shown in Fig. 3. Secured to the lower end of this rod 87 is a valve piston 88, which is larger in diameter than valve member 83, and which forms part of the safety means for automatically closing the stop valve 11 upon the appearance of defects in the steam mains such as pipe fractures. Above this piston 88 is a port 90 to which is connected pipe 56, and below said piston is a port 91 having a pipe connection 92 to the steam mains on the outlet side of the main stop valve 11.

In the operation of the control valve 39a, when the valve member 83 is in the uppermost posi-

tion shown in Fig. 3 in engagement with the upper seat 85, the ports 61a and 90 will be in communication with each other, so that the piston 32 will have equal boiler pressure acting on opposite sides thereof, and the upward boiler pressure acting on the valve member 30a will move said member upwardly into open position shown.

When the valve member 83 is moved downwardly into engagement with the seat 86 upon operation of the handle 48a as will be herein-after described, the ports 61a and 62a will be in communication with each other, while communication between the ports 61a and 90 is shut off. Under these conditions, the underside of the piston 32 will be under low exhaust steam pressure, so that the resultant downward steam pressure acting on said piston will move the valve member 30a in position to close the main stop valve 11.

If anything should happen to the steam mains such as a pipe fracture or a substantial leak, which would cause the pressure in said mains to drop below a predetermined amount, this reduction in pressure on the underside of the safety valve piston 88 will cause said piston to move downwardly from the position shown in Fig. 3, independently of the position of the handle 48a, until the valve member 83 seats on the seat member 86. In this position of the valve member 83, the stop valve 11 will be moved in closed position in the manner already described, and the fuel valve 10a will be closed at the same time as will be described.

The connection between the valve stem 84 and the crank handle 48a includes a crank shaft 100, affixed to said handle, and having a rotative slide connection with a collar 101, threaded on a sleeve 102 affixed to the casing 81. This slide connection is desirably formed by having the lower portion of said shaft of rectangular cross-section extend loosely into an aperture of corresponding cross-section in the collar 101.

A cross-piece 103 is threaded or otherwise secured to the upper end of the valve stem 84, and secured to the collar 101 by a lost motion connection, which permits the axial downward movement of said stem by steam pressure action on the safety piston 88 as already described, independently of the position of the handle 48a. This lost motion connection comprises a bolt or pin 104, having its upper end secured to the collar 101, and passing loosely through the top wall of the cross-piece 103.

Stem 84 passes through a guide member 107 secured to the casing 81, and is urged upwardly by a coil spring 108 abutting the flange of a cup-shaped member 109. Extending partially in this member 109 is a sleeve nut 110 threaded to the stem 84, and having a flange seated on the flange of the member 109. The tension of the spring 108 can be adjusted by turning the sleeve nut 110 the desired extent.

Rotation of the handle 48a in one direction causes downward axial movement of the collar 101, until said collar reaches the cross-piece 103. Further rotation of the handle 48a moves the cross-piece 103 downwardly, and in turn the stem 84 to operate the valve 39a, and close the stop valve 11 as already described. Rotation of the handle in the opposite direction moves the stem 84 upwardly, and operates the valve 39a into the position shown in Fig. 3.

The fuel valve 10a includes the valve member 16a connected to the stem 18a, which is urged upwardly by means of the coil spring 21a. A

lever 14a pivotally supported at 112 has one forked end engaging the cross-piece 103, so that said lever is moved angularly about its pivotal support as said cross-piece moves up or down, and its other end engaging the upper end of the stem 18a, to move the valve member 16a in open position shown in Fig. 3 against the action of the coil spring 21a when said cross-piece is moved upwardly.

10 In order to open the fuel valve 10a independently of the operation of the change-over valve 12a, and hold said valve in this position, there is provided a bell crank lever 114, pivoted at 115 to a frame bracket 116, and having one arm 117 thereof constituting the operating handle, and the other arm 118 serving to engage a collar 120, which is affixed to the upper end of the stem 18a, and against which the coil spring 21a acts. Extending transversely from the handle 117 is 15 a lug 121, adapted to be secured to a fixed frame arm 122 by means of a suitable locking pin 123. This valve holding mechanism is particularly useful to keep the fuel oil valve open during pre-heating and starting, and when testing the control mechanism 39, 39a.

20 If desired, the two valves 10a and 11 may be operated by remote control by mechanical or other means, for example, from the engine platform or from the deck of the ship.

25 As many changes could be made in the above construction, and many apparently widely different embodiments of this invention could be made without departing from the scope thereof, it is intended that all matter contained in the 30 above description or shown in the accompanying drawings shall be interpreted as illustrative and not in a limiting sense.

35 Having thus described my invention, what I claim as new and desire to secure by Letters 40 Patent is:

1. A steam power plant mechanism comprising a main stop valve on the outlet side of a power plant steam boiler, the outlet side of said valve being connected to steam mains leading to the 45 prime movers of the power plant, a control piston for said stop valve having boiler pressure acting on one side thereof, a change-over valve comprising a reciprocable valve member, a first pipe connection from a source of boiler pressure to 50 said change-over valve, a second pipe connection between said change-over valve and the other side of said piston, and a third pipe connection to said change-over valve from a source of steam pressure substantially lower than the boiler pressure, means for establishing communication between said second and said third pipe connections through said change-over valve, and for shutting off communication between said first pipe connection and the other pipe connections, 55 when said change-over valve is operated in one position to close said main stop valve, and for shutting off communication between said second and third pipe connections, and establishing communication between said first pipe connection and said second pipe connection, when said 60 change-over valve is operated into another position to open said stop valve, a safety piston movable with said valve member, the steam pressure in said first pipe connection acting on one side of said safety piston, and a pipe connection from the other side of said safety piston to the steam mains on the outlet of the main stop valve, said 65 safety piston being of such area, that when the pressure in said steam mains falls below a predetermined amount, the differential pressure 70

acting on said safety piston is sufficient to move said valve member into position to close the main stop valve, independently of the position of said change-over valve.

2. A steam power plant mechanism comprising a main stop valve on the outlet side of a power plant steam boiler, the outlet side of said valve being connected to steam mains leading to the prime movers of the power plant, a control piston for said stop valve having boiler pressure acting on one side thereof, a change-over valve comprising a reciprocable valve member, a first pipe connection from a source of boiler pressure to said change-over valve, a second pipe connection between said change-over valve and the other side of said piston, and a third pipe connection

to said change-over valve from a source of steam pressure substantially lower than the boiler pressure, and means for establishing communication between said second and said third pipe connections through said change-over valve, and for shutting off communication between said first pipe connection and the other pipe connections, when said change-over valve is operated in one position to close said main stop valve, and for shutting off communication between said second and third pipe connections, and establishing communication between said first pipe connection and said second pipe connection, when said change-over valve is operated into another position to open said stop valve.

RICHARD KÖLLER.
